CLOTH LAYING-UP MACHINE

Nathan Obedin, Brooklyn, N. Y.

Application August 9, 1945, Serial No. 609,850

5 Claims. (Cl. 270—31)

1

This invention relates to cloth laying-up machines for supporting a bolt of cloth to be placed in superposed layers of equal lengths on a cutting table.

An object of this invention is to provide a cloth laying-up machine comprising a cloth carrying frame pivotally mounted in superposed relation over a reciprocable frame, the reciprocable frame having adjustable arms for supporting fabric over a cutting table, means for automatically raising the arms a predetermined distance from the table for every rotation of the pivotal frame, and latch means resiliently mounted at one end of the reciprocable frame and adapted for engagement with bolt receiving means on both ends of the pivotal frame for locking the frames in unitary relation after each rotation of the pivotal frame.

Another object of this invention is to mount ball bearings in horizontal alignment at opposite ends of the reciprocable frame with their upper surfaces lying in a single plane and providing levelling means for automatically adjusting the pivotal frame to a level plane after each rotation of the pivotal frame to facilitate engagement of the latch means.

Another object of this invention is to provide a latch bolt resiliently mounted for upward movement at one end of the reciprocable frame and to provide latch bolt receiving means fixed at each end of the pivotal frame for automatically locking the frames in unitary relation after each rotation of the pivotal frame.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a side elevation of the cloth laying-up machine embodying the features of this invention.

Figure 2 is a front elevation of the cloth laying-up machine shown in Figure 1.

Figure 3 is a cross-sectional view of mechanism for automatically and equally moving the laying-up or guide rollers to and from the table, the section being taken as on line 3—3 in Figure 2.

Figure 4 is a view of a fragmentary portion of the mechanism shown in Figure 3.

2

Figure 5 is a front view of lock bolt mechanism and latch means for locking the frames in unitary relation.

Figure 6 is a cross-sectional view, the section being taken as on line 6—6 in Figure 5.

Figure 7 is a front view of ratchet mechanism for raising fabric supporting arms.

Figure 8 is a cross-sectional view, taken as on line 8—8 in Figure 7.

10 In the illustrated embodiment of the invention, the numeral 10 indicates a cloth laying-up machine comprising upper and lower frames. The lower frame 11 is slidably or reciprocably mounted on a cutting table 12. The frame 11 has end walls 13, 13'.

The end walls are secured by threaded tubes 14, 14' passing through the walls. Threaded nuts 15 engage the threads on the tubes on opposite sides of the end walls and maintain the end walls in space-apart relation.

20 Grooved wheels 17 are rotatably mounted on studs 18 in legs 19 at the lower portion of the end wall 13 and rest upon a track 20 mounted on one side of the cutting table 12. The end wall 13' is supported by non-grooved or plain rubber wheels 21 rotatably mounted similar to the mounting of the grooved wheels 17 and rest directly on the cutting table 12.

25 The upper or carrier frame identified by the numeral 22 is mounted on a pivot centrally of the slidable frame. The carrier frame 22 is rotated at the end of each reciprocation of the slid-
30 able frame to expose the fabric with the same face in an upward direction. The frame 22 has end walls 24 which extend upwardly and termi-
35 nate in bifurcated upper ends 25 adapted to re-
ceive a shaft 26 for supporting a roll of cloth indicated by dot-and-dash lines 27. A suitable sheet metal cover 28 is secured to and covers the tubes 14.

30 The roll of cloth 27 which is to be laid-up on the table 12 is supported on the shaft 26. For the purpose of keeping the fabric in an even plane as it is laid-up on the table, the machine comprises guide rollers 30, 31 mounted on two arms 32, 32 which are mounted on pivots 33, 33. The pivots extend respectively from the walls 13 and 13'.

35 As shown in Figure 1, the oppositely disposed rollers 30, 31 and the pivots 33, 33 are spaced apart equally from the shaft 26.

For the purpose of equally moving both arms in the same direction relative to the table as de-
40 termined by the height of the cloth laid-up, the ends of the arms opposite the rollers have pins

34 fixed therein and extending crosswise from the arms. An elongated horizontally positioned connecting member 35 has elongated slots 36 in which the pins 34 are slidably mounted.

The connecting member 35 has vertically positioned rectangular guide bars 40 secured thereto in any suitable manner, such as by pins 41. The guide bars 40 are spaced apart and form between them a channel 42.

A vertically elongated rectangular bar 43 is fixed to each end wall by bolts 44. Each bar 43 has an elongated slot 45 centrally thereof. The cross-sectional dimensions of the bar 43 are made to permit the connecting member 35 to be freely slidable in contacting relation therewith.

A hand knob 46, having an integrally threaded bar 47 passing through the slot 45, is in threaded engagement with the connecting member 35. By adjusting the hand knob, the connecting member 35 may be frictionally secured to the rectangular bar 43 in selected vertical positions.

By slightly unscrewing the hand knob, the connecting member 35 is released from excessive frictional restraint. It is thus possible, by moving the laying-up rollers on one side of the carriage 11 from the table 12, to cause both connecting members 35 at opposite end walls 13, 13' to move vertically and to cause the roller on the opposite side of the carriage to move equally vertically in the same direction from the table.

Fixed to the central portion of the rotatable upper frame 22 is a cylindrical housing 50 rotatably receiving a pivot 51 which is fixed to the central portion of the slidable lower frame 11. The upper frame is thus rotatably mounted in superposed relation with the lower frame.

For the purpose of automatically raising the end portions of fabric carrying arms 32 every time the pivotal upper frame 22 is moved through an angle of 180 degrees, I have provided intermittent mechanism 60 at each end of the slidable frames 11. The mechanism 60 comprises ratchet wheels 61 fixed to shafts 62 which are rotatably mounted in housings 63 fixed at each end of the slidable frame 11.

Each shaft 62 has a cam 64 fixed thereto. The lower faces of the cams contact the upper surfaces of the vertically slidable connecting members 35.

An oscillating arm 66 is mounted on each shaft 62. A pawl 67 is pivotally mounted on a pin 68 in the arm 66, and engages a tooth of the ratchet wheel. When the arm 66 is swung in the direction of the arrow, the pawl carries the ratchet wheel around one tooth length. A striker 69 fixed at each end of the pivotally mounted upper frame 22 actuates the pawl every time this frame is rotated. This movement is transferred by the cams 64 to the vertically slidable members 35 which actuate the fabric carrying arms 32 and cause end portions of the arms to rise above the cutting table an equal distance for every rotation of the pivotal frame. It is obvious that the pawl and ratchet mechanism on the far wall 13' is arranged in reverse position when viewed from the position shown in Figure 7. I may provide roller friction clutches in place of the ratchet wheels when very small rising motions are required.

As best shown in Figures 5 to 7 inclusive, I have provided latch means 70 for locking the pivotal frame 22 to the slidable frame 11 after each rotation of the pivotal frame.

The latch means 70 comprises two superposed brackets 71 and 72 fixed to a side wall 13 of the

frame 11. The brackets 71, 72 have aligned apertures 73 serving to jointly support a lock bolt 74 in upright position.

A compressed coil spring 75 is mounted on the lock bolt 74 and is held in compressed position between the brackets 71 and 72. A pin 76, passing through the lock bolt 74 and resting on the spring 75, causes the lock bolt to be supported with its upper end considerably above the top bracket 71. The lock bolt is thus resiliently supported and when moved downward and released is automatically returned to its normal upper position by the spring.

Fixed to diametrically opposite end portions of the pivotal frame 22 are brackets or bolt receiving means 77 having apertures 78 in alignment with the lock bolt when these are brought into superposed relation. When the lock bolt 74 enters an aperture 78, the frames 11 and 22 are locked in unitary relation.

As best shown in Figures 7 and 8, a ball bearing 80 is rotatably mounted on one of the walls 13 of the frame 11 and positioned opposite the locking means 74. The upper surface of the ball bearing is positioned above the upper surface of the wall 13.

As best shown in Figure 2, another ball bearing 80 is similarly mounted on the opposite wall 13' of the frame 11. The two bearings are in horizontal alignment at opposite ends of the frame 11, with their upper surfaces lying in a single plane and provide leveling means for automatically adjusting the pivotal frame 22 to a level plane after each rotation of the pivotal frame. This arrangement facilitates engagement of the latch means 70, whereby the lock bolt 74 engages the bolt-receiving means 77. It is to be noted that the outer portion of the bolt-receiving means 77 is curved upwardly and this also facilitates the engagement of the lock-bolt 74 with the aperture 78 in the bolt-receiving means 77.

A coil spring 82 has one end suitably secured to the arm 66 and the other end to the housing 63. The spring 82 serves to return the arm 66 into abutment with a stop 83 on the housing 63 when the arm 66 is released by the striker 69. It is to be noted that the pawl 67 has sufficient weight so that it drops into successive ratchet teeth in the ratchet wheel on the return movement of the pawl.

The walls 24 of the pivotal frame 22 are interconnected by pairs of spaced-apart parallel horizontal rods 85, 86, one pair on each side of the frame 22.

The cloth from the roll 21 passes between the guide rods 85, 86 and between the guide rollers 30, 31. The laying of the cloth in layers is as follows: One end of the cloth is first placed on the table 12 and an elongated bar 87 of considerable weight is placed on the end of the cloth. The cloth laying-up machine 10 is then moved to the opposite end of the table. During such movement the cloth unwinds from the roll of cloth 21. The cloth may then be cut and a similar bar placed on that end of the cloth. The pivotal frame 22 may then be rotated about the pivot 51 through an angle of one hundred and eighty degrees. The free end of the cloth is then threaded through the opposite rod 85 over the tubes 14, 14' and guide rollers 30 and 31 at the opposite side of the carriage 11. The free end of the cloth is then placed under the last bar. The machine is then moved to the starting end of the table to lay another length of cloth and reversed. These operations are repeated, the frame

being moved back and forth until the desired number of layers have been laid up on the table with the right side of all the layers of cloth facing up or down as desired.

In accordance with the patent statutes I have described and illustrated the preferred embodiment of my invention, but it will be understood that various changes and modifications can be made therein without departing from the spirit of the invention as defined by the appended claims.

I claim:

1. In a cloth laying-up machine comprising a cutting table and a frame reciprocably mounted on said table, a cloth carrying frame pivoted and rotatably mounted on said reciprocable frame, adjustable arms adjustably mounted upon said reciprocable frame, rods carried by said arms for supporting fabric over said cutting table, and means whereby rotation of said pivoted frame automatically raises said arms a predetermined distance from said table.

2. In a cloth laying-up machine comprising a cutting table and a frame reciprocably mounted on said table, a cloth carrying frame pivoted and rotatably mounted on said reciprocable frame, adjustable arms adjustably mounted upon said reciprocable frame, rods carried by said arms for supporting fabric over said cutting table, means whereby rotation of said pivoted frame automatically raises said arms a predetermined distance from said table, a bearing rotatably mounted at each end of said reciprocable frame for leveling said pivoted frame, and latch means in alignment with said bearings for automatically locking said frames in unitary relation after being levelled.

3. In a cloth laying-up machine comprising a cutting table and a frame reciprocably mounted on said table, a cloth carrying frame pivoted and rotatably mounted on said reciprocable frame, adjustable arms adjustably mounted upon said reciprocable frame, rods carried by said arms for supporting fabric over said cutting table, means whereby rotation of said pivoted frame automatically raises said arms a predetermined distance from said table, a rotatable bearing mounted on a horizontal axis at each end of said reciprocable frame for leveling said pivoted

frame, and latch means in alignment with said bearings for automatically locking said frames in unitary relation after being levelled.

4. In a cloth laying-up machine comprising a cutting table and a frame reciprocably mounted on said table, a cloth carrying frame pivoted and rotatably mounted on said reciprocable frame, adjustable arms pivotally and adjustably mounted upon said reciprocable frame, rods carried at end portions of said arms for supporting fabric over said cutting table, means whereby rotation of said pivoted frame automatically raises said arms a predetermined distance from said table, a rotatable bearing mounted on a horizontal axis at each end of said reciprocable frame, the upper surfaces of said bearings lying in a horizontal plane for supporting and leveling said pivoted frame, and latch means mounted on said frames and in alignment with said bearings for automatically locking said frames in unitary relation.

5. In a cloth laying-up machine comprising a cutting table and a frame reciprocably mounted on said table, a cloth carrying frame pivoted and rotatably mounted on said reciprocable frame, adjustable arms pivotally and adjustably mounted upon said reciprocable frame, rods carried at end portions of said arms for supporting fabric over said cutting table, vertically slideable members respectively connecting two of said arms, cams rotatably mounted on said reciprocable frame and contacting said connecting members, ratchet means mounted on said reciprocable frame for intermittently actuating said cams, and strikers at each end of said pivotal frame for actuating said ratchet means, whereby rotation of said pivoted frame automatically raises said arms a predetermined distance from said table.
